CIGARETTE TUBE AND APPARATUS FOR
MAKING SUCH TUBES

Boris Aivaz, Budapest, Hungary

Application September 5, 1933, Serial No. 688,246
In Hungary September 17, 1932

3 Claims. (Cl. 93—77)

The invention relates to cigarette tubes which prior to filling are furnished with a filter wad or plug consisting of a multiple strip of a plurality of thicknesses of corrugated or crepe paper wound into a loose spiral.

In filling cigarette tubes equipped with smoke filter plugs, the defect has been observed that the smoke filter plug is liable to be ejected by the plunger of the cigarette filling machine.

10 In order to avoid this the present invention proposes a cigarette tube which has a smoke filter plug which is cemented into the tube prior to filling the latter.

The invention also relates to an arrangement 15 for making such tubes and comprising a device for applying adhesive which comes into operation intermittently and is disposed between a device for winding or producing the filter plug and an arrangement for filling the cigarette, said 20 adhesive applying device applying to the compressed smoke filter plug prior to its introduction into the cigarette tube a drop of adhesive which comes into contact with the tube solely on the expansion of the compressed smoke filter 25 plug on introduction so that a premature wiping off or spreading of the adhesive is avoided.

During the application of the adhesive the plug is supported by a sleeve which is associated with the mandrel carrying the tube and is longitudinally slotted the diameter of the cavity of the sleeve being smaller than the plug.

The ejection of the plug from the sleeve and its introduction into the tube is effected preferably by a blade which is rocked intermittently 35 into the path of the sleeve and which on the return motion of the sleeve retains the plug and thrusts it into the tube. The plug released from the sleeve passes during its expansion into the tube and is secured thereto by the adhesive.

40 The drawing represents by way of example an embodiment of the invention with reference to the manufacture of cigarette tubes with smoke filter plugs.

Fig. 1 shows a plan view of the device for applying adhesive.

Fig. 2 an end view of the adhesive container.

Fig. 3 a front view corresponding to Fig. 1 with the supporting mandrel for the sleeve displaced outwardly.

50 Fig. 4 is a front view corresponding to Fig. 3 in that position of the components which they assume at the moment of application of adhesive.

Figs. 5 and 7 show the supporting mandrel 55 carrying the tube and the filter plug surrounded

by the sleeve as well as the ejecting blade in two different positions.

Fig. 6 shows a plan view of the mandrel with the blade omitted.

Figs. 8-9 show details of the adhesive applying device and Fig. 10 is a side view of the sleeve coacting with the mandrel.

Fig. 11 shows the finished product, namely the cigarette tube with smoke filter plug cemented in.

By means of the plunger 12 the smoke filter plug 11 is slid from the winding device 10, Figs. 1 and 3, which device is known per se, into the cavity of a sleeve 23 which is integral with the supporting mandrel 13. In its previous advance 15 this mandrel 13 had carried along with it the cigarette tube 14 in the direction of the arrow Fig. 1. In the vicinity of the winding device 10 is the adhesive container 1, Figs. 1 and 2, the front wall 5 of which has an opening through 20 which projects the adhesive supplying disc 2 which is rotatable about the horizontal axis 4. On its periphery the disc 2 is provided with a continuous groove 3, Figs. 8 and 9. By means of the ratchet wheel 7 an intermittent motion can 25 be imparted to the shaft 4. In each position of rest of the disc 2 a drop of adhesive 17 is applied to the side of the plug 11.

The sleeve 23 has a longitudinal slot 16, Fig. 10, which extends through to the cavity 15 of 30 the sleeve and is continued along the mandrel 13, Fig. 6.

The diameter of the cavity of the sleeve 15 is somewhat smaller than the outer diameter of the plug 11 and the inner diameter of the tube 35 14 so that the plug 11 is held in the compressed state in the sleeve 23 and expands as soon as it leaves the sleeve.

On the opposite side of the adhesive applying device to the winding arrangement 10 is disposed 40 a blade 18 which pivots about a pin 19 and swings from its highest position, Fig. 4, into the working position, Fig. 5, as soon as the sleeve 23 together with the plug 11 which is resiliently compressed within its cavity has again advanced 45 after the application of the drop of adhesive 17 and has arrived in the position shown in Fig. 3. Then the sleeve 23 together with mandrel 13 again passes to the right the blade 18 entering in the slot 16 and ejecting the plug 11 from the 50 sleeve 23 and stripping the tube 14 from the mandrel 13. In this operation the drop of adhesive 17 is not smeared because it cannot pass into contact with the tube 14. It is only when the plug 11 emerges from the cavity 15 of the 55

sleeve 23 that it expands in consequence of its elasticity and is urged against the inner wall of the tube 14 and is secured in position therein by the adhesive (Fig. 11).

5 What I claim is:—

1. Apparatus for producing cigarette tubes having smoke filter plugs cemented thereon, comprising a movable mandrel for supporting the tube, a longitudinally-slotted hollow supporting device for the plug, movable simultaneously with the said supporting mandrel, and an adhesive-applying device comprising an intermittently movable disc applying a drop of adhesive to each plug through the slot while the plug is in position in the longitudinally slotted supporting device, the hollow of which supporting device is of smaller diameter than the outer diameter of the plug.
2. Apparatus for producing cigarette tubes having smoke filter plugs cemented thereon, comprising a movable mandrel for supporting the tube, a hollow supporting device for the plug in the form of a sleeve integral with said mandrel, the said supporting device and the adjacent portion of the mandrel being longitudinally slotted, and an adhesive-applying device comprising an intermittently movable disc applying an

intermittently movable disc applying a drop of adhesive to each plug through the slot while the plug is in position in the longitudinally slotted supporting device, the hollow of said supporting device being of smaller diameter than the outer 5 diameter of the plug.

3. Apparatus for producing cigarette tubes having smoke filter plugs cemented thereon, comprising a movable mandrel for supporting the tube, a hollow supporting device for the plug 10 in the form of a sleeve integral with said mandrel, the said supporting device and the adjacent portion of the mandrel being longitudinally slotted, and an adhesive-applying device comprising an intermittently movable disc applying 15 a drop of adhesive to each plug through the slot while the plug is in position in the longitudinally slotted supporting device, the hollow of said supporting device being of smaller diameter than the outer diameter of the plug, a blade pivotal in the 20 path of said supporting device, and passing into the longitudinal slot in the sleeve and mandrel, and means for driving said blade in pivotal manner.
